BURNER

Franklin H. Wells and Kemper P. Brace, South Bend, Ind., assignors to International Engineering Corporation, Chicago Ill., a corporation of Illinois

Application February 2, 1938, Serial No. 188,229

7 Claims. (Cl. 158—4)

This invention relates to burners and more particularly to fluid fuel burners for heating furnaces or the like.

One object of the invention is to provide an oil burner design which will give satisfactory performance in a furnace intended primarily for burning coal.

Another object is to provide an oil burner for converting a coal furnace into an oil burning furnace, the design of the burner being such that it will perform uniformly and acceptably in all the various types and sizes of fire pots apt to be encountered.

One of the objects of the invention is to provide, in combination with a furnace, a burner which will direct heat downwardly to the lower part of the furnace firebox. This arrangement provides more even heating of the furnace and results in increased efficiency due to the fact that it enables a larger percentage of the heat to be extracted from the combustion gases.

Another object of the invention is to provide a burner which will direct heat downwardly to cause relatively high heating of the space below it.

Still another object of the invention is to provide a burner in which a portion of the heat is reflected or radiated back into the burner. This arrangement is particularly advantageous with oil burners in which the reflected heat assists materially in vaporization of the oil.

Other objects, advantages and novel features of the invention will be apparent from the following description when read in connection with the accompanying drawings, in which:

Figure 1 is a central section of a furnace including a burner embodying the invention;

Figures 2, 4, and 5 are partial views similar to Figure 1 showing modified constructions;

Figure 3 is a view on the line 3—3 of Figure 2; and

Figure 6 is a vertical section through part of another embodiment.

Figure 1 illustrates a furnace of the type having a vertical cylindrical firebox 10 surrounded by a jacket 12 for circulation of a heat transfer medium such as air, water or the like. The upper part of the firebox is connected to a flue 14 leading to a stack or the like as will be understood. The furnace is provided with a side opening 16 normally closed by the usual fire door but closed according to the present invention by a plate 18 to support a burner 20.

As illustrated herein the burner 20 is of the conversion type and is constructed as more

particularly described and claimed in the copending application of Kemper P. Brace, Serial No. 145,706 filed June 1, 1937, and includes a substantially horizontal tube or conduit 22 supported by the plate with its inner end turned down slightly. A hollow burner body 24 having a series of primary air inlet openings 26 is secured in the tube 22 and carries a porous refractory block 28 formed with a series of parallel horizontal longitudinal bores or passages. Oil or an equivalent liquid fuel is supplied to the block through a pipe 30, and seeps through the porous structure of the block and air is circulated past and through the block by the suction from the chimney, assisted if necessary by a motor driven fan 32 carried by the burner body, and takes up the fuel in passing through the horizontal passages therein. A disc 34 adjustably secured to the end of the tube 22 serves to regulate the air supply.

With furnaces of the type so far described the hot combustion products issuing from the burner have a tendency to rise directly to the top of the firebox heating it to a high degree but leaving the lower part of the firebox relatively cool. This results in a slow rate of heat transfer to the circulating medium due to the fact that it is heated only in the upper part of the furnace, and in a loss of efficiency due to the fact that the gases flowing out the top of the firebox to the stack have had only a short contact with the jacket and are at a relatively high temperature.

According to the present invention means are provided to deflect heat to the lower part of the firebox to overcome the above-mentioned defects. As shown in Figure 1 such means is constituted by a curved tube 36 of suitable refractory material, as for example stainless steel, connected to the discharge end of the tube 22 and having a bell shaped discharge end facing downwardly in the firebox. A curved portion of the tube wall lies in front of the discharge end of the tube 22 and, when heated, becomes incandescent and radiates heat back into the tube directly upon the face of the porous block 28 of the burner, to assist in vaporizing the oil in the member 28. Since the discharge end of tube 36 is below the level of the tube 22, an opening 38 is preferably provided in the top part thereof to permit rising of a portion of the combustion products under natural draft conditions. This is desirable in starting the burner to establish a draft in the stack.

In operation of this construction flame from the burner will be directed downwardly to heat the lower part of the firebox and will rise around the tube 36 to heat the upper part of the firebox.

Since the hot combustion products travel over a relatively long path in the firebox a large percentage of the heat will be extracted therefrom thereby increasing the furnace efficiency. At the same time transfer of heat from the firebox to the circulating medium will be improved due to heating of the entire jacketed portion of the furnace.

During operation the tube 36 will be heated to a high degree and the portion thereof opposite the discharge end of the burner tube 22 will radiate heat back into the burner. This insures heating of the porous element 28 and assists in proper vaporization of the oil and in the combustion thereof.

Figures 2 and 3 illustrate a modified construction including a flat deflector plate 40 having down-turned edges secured to the tube 22 and extending outwardly therefrom. A second deflector member 42 is secured to the lower part of tube 22 and has a reflector portion 44 lying in front of the discharge end of the tube 22.

In operation of this form the plate 40 deflects heat to the lower part of the firebox and portion 44 of the member 42 serves to radiate heat back into the burner.

In the embodiment of Figure 4 a single plate 46 having a down-turned flange 48 is secured to the upper part of the burner tube 22 with the flange 48 lying in front of the burner tube discharge end. Both plate 46 and flange 48 deflect heat to the lower part of the firebox and at the same time the flange 48 serves to radiate heat back into the burner.

The embodiment of Figure 5 includes a curved tube 50 secured to the end of burner tube 22 with its discharge end facing up. A deflector disc 52 is secured over the end of tube 50 in spaced relationship thereto as by means of a supporting rod 54. The disc 52 serves to deflect heat rising through tube 50 downward toward the lower part of the firebox and that portion of tube 50 which is in front of the tube 22 serves to radiate heat back into the burner.

Figure 6 illustrates an embodiment including a square-section downwardly-opening deflector 60, one side of which serves to radiate heat back against the porous vaporizing element 28, and which has a top opening 62 corresponding to the opening 38.

While several embodiments of the invention have been illustrated and described in detail, it will be understood that many changes might be made therein and it is not intended to limit the scope of the invention to the forms shown or otherwise than by the terms of the appended claims.

What is claimed is:

1. In combination with a furnace having a firebox and a side opening, a burner projecting through said side opening and adapted to discharge a flame substantially horizontally of the firebox, said burner comprising a porous block of refractory material having horizontal parallel air passages therethrough and opening into the firebox, and said burner having means for supplying fuel to seep through the porous structure of said block and be taken up by the air in said passages, and a deflector of refractory material having a part adjacent the discharge end of the burner for deflecting a portion of the heat of the burner to the lower part of the firebox and having a part highly heated by the flame and radiat-

ing heat back into the burner upon the face of said porous block to heat the air and fuel mixture issuing from said passages.

2. In combination with a furnace having a firebox and a side opening, a burner projecting through said side opening and having a porous vaporizing element having passages in which air takes up fuel seeping through said element and adapted to discharge a flame substantially horizontally of the firebox, and a deflector overlying the discharge end of the burner for deflecting a portion of the heat of the burner to the lower part of the firebox, said deflector including an integral part lying in front of the burner and highly heated by said flame to radiate heat back upon the vaporizing element.

3. In combination with a furnace having a firebox and a side opening, a burner projecting through said side opening and adapted to discharge a flame substantially horizontally of the firebox, and a deflector tube secured over the end of the burner and having a discharge end facing downwardly to deflect heat to the lower part of the firebox, said tube having an opening in the upper part thereof to form a by-pass for a portion of the combustion products.

4. In combination with a furnace having a firebox and a side opening, a burner projecting through said side opening and adapted to discharge a flame substantially horizontally of the firebox, a substantially horizontal deflector plate secured over the discharge end of the burner to deflect heat to the lower part of the firebox, and a second deflector member secured to the lower part of the burner and including a portion lying in front of the burner discharge to reflect heat back into the burner.

5. In combination with a furnace having a firebox and a side opening, a burner projecting through said side opening and having a fuel and air mixing element and adapted to discharge a flame substantially horizontally of the firebox, and a curved tube secured over the end of the burner and formed with a bell-shaped end facing downwardly and including an integral portion lying in front of the burner discharge end to radiate heat back into the burner.

6. In combination with a furnace having a firebox and a side opening, a burner projecting through said side opening and having a porous element through which fuel seeps and which has means for mixing the fuel and air and adapted to discharge a flame substantially horizontally of the firebox, a curved tube secured over the end of the burner with its discharge end facing upwardly and the front wall of which is highly heated by said flame and radiates heat back upon the face of the mixing element, and a substantially horizontal deflector overlying the discharge end of the tube to deflect heat to the lower part of the firebox.

7. A fuel burner comprising a hollow burner part from which a flame is adapted to issue and a substantially horizontal plate secured to said part and extending outwardly above the discharge end thereof to deflect heat downward and a member secured to the part and extending outwardly below the discharge end thereof and having an upturned portion lying in front of the burner discharge to reflect heat back thereinto.
